(57) **CLAIM**

An ornamental design for a garage door cam, as shown and described.

DESCRIPTION

FIG. 1 is a right front isometric view of a garage door cam according to one embodiment of this invention;

FIG. 2 is a right rear isometric view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a right front isometric view of a garage door cam according to another embodiment of this invention;

FIG. 10 is a right rear isometric view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The dash-dash style of broken line showing of cam structure is included for the purpose of illustrating portions of the garage door cam and forms no part of the claimed design. The dash-dot-dash style of broken line in FIGS. 9, 10, and 15 is included for the purpose of illustrating the boundaries of the claim and forms no part of the claimed design.
